Johns Contrell, Jr.

BY Fred C. Traenitzel, ATTY.

UNITED STATES PATENT OFFICE.

JOHN CONTRELL, JR., OF NEWARK, NEW JERSEY.

TOY.

SPECIFICATION forming part of Letters Patent No. 426,113, dated April 22, 1890.

Application filed July 22, 1889. Serial No. 318,184. (No model.)

To all whom it may concern:

Be it known that I, JOHN CONTRELL, Jr., a citizen of the United States, residing at Newark, in the county of Essex and State of New Jersey, have invented certain new and useful Improvements in Toys; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

My invention relates to improvements in mechanical toys designed for the amusement of children; and it consists, essentially, of a board provided with a fort having arranged thereon a rotating gun in connection with a figure secured to the top of a lid of a box having concealed therin a second figure actuated by a spring and adapted to jump out of the box when the lid is thrown back when the figure on the lid has been struck with a ball fired from the gun on the fort.

The invention consists, further, in certain details of construction and novel combinations of parts, which will be hereinafter more fully described, and finally pointed out in the clauses of the claim.

The invention is illustrated in the accompanying sheet of drawings, in which similar reference-letters are employed to indicate like parts in each of the several views.

In said drawings, Figure 1 represents a vertical section of my improved toy, the ball from the gun being shown about to strike the figure on the box. Fig. 2 is a similar view illustrating the "jack in the box" in the act of jumping from the box, and Fig. 3 is a plan view of the gun in its operative position and a base or fort upon which the cannon or gun is arranged.

In said drawings, A designates the main frame upon which the toy is mounted. Upon one end of the frame A is arranged the base or fort B, which is cylindrical and hollow. Within this base is placed a post b, to the upper end of which is secured the grooved block or table b'. Said post fits into a pedestal-block b³, arranged within the bottom of the base, as shown, the said pedestal thereby

serving to hold the post b in an upright position and allowing the gun-carrying block or table b' to rotate about its vertical axis in a horizontal plane. The block b' is preferably inclined in the direction toward the figure shown on the right of the drawing, represented in Fig. 1, and is provided with a groove b² in the top thereof, in which is placed the gun or cannon c. This gun is of the ordinary construction, being provided with a rod or stem c', arranged within the bore of the gun and provided with a piston or plate c², and projecting at the opposite end through the gun, and having a finger-piece c³, by means of which the rod is drawn back to enable the firing of the ball d from the gun. The rod c', when released by the operator, is caused to return to its normal position by an elastic band c⁴, secured thereto and to the gun in any well-known manner; or I may employ an ordinary spiral spring arranged around the stem, if desirable. Upon the opposite end of the frame A is arranged a box E, provided with a lid e, and firmly secured on the top of said lid is a figure F, designating that of a man. Pressed down within the box E underneath the closed lid is a second figure G, dressed in a long gown g, and concealed therebeneath is a spiral spring g'. A hook e' is secured by means of an eye e² to the side of the box E, said hook being adapted to engage with a pin e³ on the lid when closed, thereby causing the retention of the "jack" in the box.

When it is desired to operate the toy, the ball d is placed in the gun in front of the piston, and the rod c' is drawn back by the finger-piece to the position indicated in Fig. 3. After taking aim for the figure F on the box E the finger-piece is let go and the elastic band c⁴ causes the rod c' to return and the ejection of the ball d from the gun. When the aim has been a perfect one, the ball from the gun will strike the figure upon the box E and cause the disengagement of the hook e' from its pin e³. As soon as the hook has been released from its holding-pins the spring g' in the doll G causes the lid e to assume the position indicated in Fig. 2, and the spring-actuated doll is at liberty to jump from the interior of the box E.

If desirable, a string g² may be attached to

a block on the lower end of the spring g' , said string also being fastened within the box, as shown in Fig. 2.

The balls used in connection with this toy 5 may be of wood or rubber or of any other suitable material, and instead of representing a human being on the lid of the box I may place thereon a figure representing an animal.

The gun c may be permanently secured in 10 the groove in the rotating table by means of metallic bands c^5 , or the same may be detachably arranged in said groove.

Having thus described my invention, what I claim is—

15 1. In a toy, the combination, with a rotating table, of a gun and operating means therefor whereby said gun is caused to present a ball from its nozzle, and a box having a lid and a figure thereon, and means on said box 20 for holding said lid in its closed position until released therefrom when said figure on the lid is hit by the ball from the gun, thereby causing the lid to fly back, for the purposes set forth.

25 2. In a toy, the combination of a base B , having a rotating table thereon, a gun on said table in a groove therein, and means for operating said gun and causing the ejection of a ball therefrom, a box having a lid and a figure thereon means for holding said lid in its 30 closed position until released when said figure has been hit by a ball from the gun, and a second and spring-actuated figure concealed in said box, which is released therefrom when

the lid has been thrown back, as and for the purposes set forth.

3. In a toy, the combination of a base B , having a rotating table thereon, said table being inclined and provided with a groove across the top thereof, a gun on said table in 40 said groove therein and means for operating said gun and causing the ejection of a ball therefrom, and a box having a lid and a figure thereon, and means for holding said lid in its closed position until released when said 45 figure has been hit by a ball from the gun, and a second and spring-actuated figure concealed in said box, which is released therefrom when the lid has been thrown back, and a string secured to said spring-actuated figure and to the box, as and for the purposes set forth.

4. In a toy, a gun and operating means therefor by means of which said gun is caused to present a ball, in combination with a box 55 having a lid and a figure thereon adapted to be hit by the ball from the gun, and a figure concealed within said box and caused to appear above the box when the lid has been thrown back, as set forth.

In testimony that I claim the invention set forth above I have hereunto set my hand this 20th day of July, 1889.

JOHN CONTRELL, JR.
